AWNNG

Tandy Burr Thurman, Kansas City, Mo.

Application August 1, 1942, Serial No. 453,151

12 Claims. (Cl. 160—62)

This invention relates to awnings for protecting windows or similar openings, and has for its principal object to provide an exterior awning structure adapted for ready adjustment at selected angles to exclude rain and other elements and which is equipped with louvers arranged to pass air and light.

Other objects of the invention are to provide an awning structure composed of standard size units whereby an awning of any desired width may be assembled by adding the required number of units; to provide an awning with removable transparent panels so that it is adapted for use as a storm sash; to provide an awning of simple, inexpensive construction and having free acting joints that are easily manipulated from the inside of the window; and to provide an awning construction particularly adapted to be formed of available material, such as wood.

In accomplishing these and other objects of the invention, as hereinafter pointed out, I have provided improved details of structure, the preferred forms of which are illustrated in the accompanying drawings, wherein:

Fig. 1 is a perspective view of an awning constructed in accordance with the present invention and composed of two units, the awning being shown as applied to a window of a building.

Fig. 2 is a horizontal section through the window frame and awning showing the awning in closed position over the window opening in the manner of a blind or shutter.

Fig. 3 is a fragmentary perspective view of the parts composing one of the hinge joints, the parts being shown in spaced relation.

Fig. 4 is a vertical section showing the awning in projecting position.

Fig. 5 is a similar section showing the awning in closed position.

Fig. 6 is a detail section through an awning equipped with a modified form of hinge joint.

Referring more in detail to the drawings:

I designates an awning constructed in accordance with the present invention and which is adapted to be mounted as a complete assembly on the exterior side of a window 2. The awning assembly includes a frame 3 consisting of side stiles 4 and 5, and top and bottom rails 6 and 7 secured together at the ends with any common cabinet joint. The frame 2 is of a size corresponding to the window and is preferably mounted upon the face sides of the window casing 8 by fastening device, such as screws 9, that are extended through the frame members and into the window casing.

5 Mounted within the frame 2 are one or more awning units 10, depending upon the width of the frame. For example, the awning illustrated is composed of two units, each of which includes an upper section 11 and a lower section 12 interconnected by hinge joints 13. The upper section includes side bars 14 and 15 having a series of spaced grooves 16 formed in the facing sides thereof and sloping downwardly from adjacent 10 the inner edges 17 of the side bars toward the front edges 18 to mount the ends of slat-like louvers 19 which may be standard Venetian blind stock. The louvers are spaced apart to provide air passageways 20 therebetween of a width so that the lower edge 21 of an upper louver substantially registers with the upper edge 22 of a lower louver so that when the awning is in closed position, as shown in Fig. 5, the louvers obstruct direct rays of light from passing through the window. However, a portion of the light rays striking the upper faces 23 of the louvers is reflected onto the under surfaces 24 of an adjacent upper louver and directed through the window to provide adequate illumination without the glare of the direct rays of light. The lower section also includes side bars 25 and 26 having louvers mounted in the same manner as the upper section just described.

20 The adjacent ends of the side bars are provided with half joints by notching the outer sides of the upper bars and the inner faces of the lower bars so as to provide lapping tongue-like portions 27 and 28 that are interconnected by pivot members, such as pins 29.

30 35 In order that the hinge joints freely operate, the upper, inner corners of the side bars of the lower section are rounded as at 30, and the inner, lower corners of the side bars of the upper section are cut at a slight angle, as indicated at 31. 40 to allow the lower section to be located in a substantially horizontal position when the awning is in fully projected position shown in Fig. 4. The inner, lower corners of the side bars of the upper section are also rounded similarly to the bars of 45 the lower section.

The lower ends of the side bars for the lower section are connected by a cross-bar 32 that is adapted to seat upon the upper face of the bottom cross-rail 7, as shown in Fig. 5. The upper 50 ends of the side bars for the upper section are interconnected by a cross-bar 33 at a point just above the uppermost louver and the cross-bar is arranged so that the inner face 34 thereof seats against the outer face of the window casing 55 when the awning is in closed position.

In order to permit projection of the awning, the upper edge of the bar 33 is bevelled, as at 35, to provide sufficient clearance as the awning is swung outwardly upon hinge pins 36. The hinge pins are fixed within the ends of the side bars and project into sockets formed in the inner face of the stiles 4 and 5 of the frame 2.

Attention is directed to the fact that the dowels comprising the hinge joints are of sufficient length so as to provide clearance between the tongues 28 and 29 of the hinge connections and between the outer face of the side bars 17-18 and the inner faces of the side stiles 4-5.

The upper ends of the side bars 14 and 15 of the upper sections also carry a drip rail 37 located at substantially the same angle of inclination as the louvers and having the front edge 38 thereof projecting outwardly from the plane of the louvers, as shown in Figs. 4 and 5. In order to further strengthen and maintain proper spacing of the side bars, they are interconnected by tie rods 39 and 40 positioned between selected louvers of the respective sections. The lower section is adapted for guided support within vertical grooves 41 and 42 located in the facing sides of the side stiles 4 and 5, as shown in Fig. 4, the ends of the side bars being provided with pins 43 which project into the grooves. To facilitate sliding movement, the side bars may be provided adjacent the pin with chair glides 43' which bear upon the inner side faces of the stiles 4 and 5. To facilitate adjustment of the awning from the interior of the window opening, the lower cross-rail of the upper sash may be provided with a bracket 44 having an opening 45 therein for passing a lifting cord 46, one end of which is secured to an eye 47 projecting from the center of the lower cross-bar 32, while the other end is adapted to anchorage to a suitable fixture 44' applied to the inner side of the window frame. In order to secure the awning in any selected position thereof the upper section carries an eye 47' to which is connected a cord 46' that also extends through the opening 45 and the free end thereof is adapted to be anchored to the fixture 44'. When both cords are drawn taut and secured to the fixture 44', the awning is securely positioned, free from rattles, and is not affected by gusts of wind.

The units may be connected by placing the adjacent side bars in face to face contact and securing them in position by suitable fastening devices, such as screws 48.

In order that the awning may also be utilized as a storm sash, the inner faces of the side bars are provided adjacent the rear edge of the louvers with grooves 49 and 50 to accommodate the edges of a transparent panel 51 that is slid thereinto from the lower ends of the side bars and which has the upper edge 52 thereof engaged in a similar groove 53 in the upper cross-bar 33. The lower ends of the grooves 49 and 50 are closed by a slat 54 having its ends engaged in the grooves 49 and 50 and connected with a cross-slat 55 which bridges the space between the lower edge of the panel and the inner face of the lowermost louver, as shown in Fig. 4. The ends of the cross-bar 55 are mounted in grooves 56 formed in the inner faces of the side members. The lower edge of the glass panel seats upon the inner edge of the cross-slat 55 so that substantially closed joints are provided about the marginal edges of the panel. The side members of the lower frame are provided with similar grooves 57 to mount 75

a transparent panel 58 which is of sufficient length so that the upper edge 59 abuts against the lower edge of the slat 54 when the awning is in closed position as shown in Fig. 5.

5 In the form of the invention shown in Fig. 6, the adjacent ends of the side bars 60 and 61 of the upper and lower sections are cut on an angle parallel with the angles of the louvers 62 and the side bars are connected together with ordinary hinges 63 applied to the inner edges thereof, as shown in Fig. 6. Otherwise the construction is the same as that specified in connection with the preferred form of the invention.

15 In installing an awning constructed and assembled as described on the exterior of a window frame, an awning composed of a number of units 10 sufficient to extend across the width of the window 2 is provided, the units 10 being of a width relative to standard size window openings 20 so that any slight variation in widths is compensated for in the width of the window casings 8. After the units are assembled in the frame 3, the frame is mounted directly against the window casing 8 and secured by the fastening devices 9. After installation of the awning the brackets 44 may be attached to the lower cross-rail of the upper sash and the raising cord 46 and anchoring cord 46' are extended therethrough.

30 To raise the awning the inner ends of the cords are loosened from their anchors and a pulling force is applied to the cord 46 which draws the lower end of the lower sections upwardly guided by the grooves 41 and 42. This movement of 35 the lower section causes the upper section to swing outwardly as shown in Fig. 4. When the awning is in adjusted position, both cords are drawn taut and the ends secured to the fixture 44'.

40 Attention is directed to the fact that the attaching point of the lifting cord 46 is off center with respect to the hinging points of the awning so that initial pull on the cord causes the hinge joints to move outwardly with a minimum effort 45 on the part of the operator.

In summer the usual window screen may be applied within the window frame in which case the lifting cord is extended through an opening 50 in the upper cross-rail in case of a half screen or the central cross-rail in case of a full screen.

55 In the winter the awning may be used as a storm sash by insertion of the transparent panels 51 and 58. In applying the panels the awning may be moved to the position shown in Fig. 4, and the lowermost panel 58 slid into the grooves 49 and 50 of the side bars 14 and 15 of the upper section 11, far enough so that the lower edge of the panel 58 passes the hinge joint, after which the awning is moved to the position shown in Fig. 5, bringing the grooves 57 in the lower side bars 25 and 26 into registry with the grooves 49 and 50 of the upper side bars 14 and 15, whereupon the lower panel may be shifted into position in the lower section 12. The awning is again raised to the position shown in Fig. 4, after which the panel 51 of the upper section 11 is inserted into the grooves 49 and 50 and retained in position by inserting the cross-slats 54 and 55. The cross-slats, being of flexible material, are easily sprung so that the ends thereof enter the grooves in which they are supported. In the summertime transparent panels may be removed by reversing the steps just described.

From the foregoing it is obvious that I have provided an awning of the louver type which

also serves the purpose of a venetian blind and a storm sash. It is obvious that the awning is of simple, inexpensive construction and may be readily applied. It is also obvious that the awning is well adapted to be constructed of wood and that the joints are free acting and will remain so even should there be slight swelling of the parts in damp weather.

What I claim and desire to secure by Letters Patent is:

1. An awning including, an upper louvered section and a lower louvered section, hinge means connecting said sections, means hinging the upper section relative to a window at the top thereof, means for guiding the lower portion of the lower section for movement vertically of said window, and a transparent panel removably carried by each of the sections whereby the awning is adapted to be used as a storm sash.
2. An awning including, louvered sections, a frame, means supporting the sections in the frame for movement from a blind-forming position with said frame to an awning-forming position, and a transparent panel carried by each of the sections whereby the awning is adapted to be used as a storm sash when in said blind-forming position.
3. An awning including, a frame, a plurality of units in the frame comprising an upper section and a lower section having hinged connection with the upper section, said sections having side bars provided with a series of groove-like recesses, louvers having ends disposed in the recesses of said side bars, tie rods between selected louvers to retain the louvers in said recesses, means connecting the units together, and means hinging the interconnected units in the frame to swing from a position in the plane of the frame to a projecting position relative to the frame.
4. An awning including, a frame, a plurality of units in the frame comprising an upper section and a lower section having hinged connection with the upper section, said sections having side bars provided with a series of groove-like recesses, louvers having ends disposed in the recesses of said side bars, tie rods between selected louvers to retain the louvers in said recesses, means connecting the units together, means hinging the upper portions of the interconnected units in the frame to swing outwardly from the frame, and means guiding the lower portion of the interconnected units for vertical movement in the frame to effect outward movement of the sections at said hinge connections.
5. An awning including, a frame, upper and lower sections having hinged interconnection, said sections having side bars provided with a series of groove-like recesses, louvers having ends disposed in the recesses of said side bars, tie rods between selected louvers to retain the louvers in said recesses, means hinging the upper section in the frame to swing outwardly from the frame, means guiding the lower section for vertical and pivotal movement in the frame to effect outward movement of the sections at said hinge connection, a lifting cord attached to the lower section, and a guide for said cord adapted for attachment to a portion of a window to which the awning is installed whereby a pulling force applied to the cord effects movement of the sections in the frame.
6. An awning including, a frame, a plurality of units in the frame comprising an upper section and a lower section having hinged connec-
5. connection with the upper section, means connecting the sections of the units together, means hinging the upper portions of the interconnected units in the frame to swing outwardly from the frame, means guiding the lower portions of the interconnected units for vertical movement in the frame to effect outward movement of the hinge connections between said sections, a transparent panel removably carried by each of the sections whereby the awning is adapted to be used as a storm sash.
10. 6. An awning including, an upper section having side bars, louvers connecting the side bars, a lower section having similar side bars, louvers connecting the side bars of the lower section, hinge means connecting the side bars of the sections, a support for swinging mounting of the upper section, guide means for the lower section to effect hinging of said hinge means when the lower section is raised in said guide means, means for raising the lower section in the guide means, and means attached to the upper section and cooperating with the raising means to anchor the sections in adjusted position.
15. 7. An awning including, an upper section having side bars, louvers connecting the side bars, a lower section having similar side bars, louvers connecting the side bars of the lower section, hinge means connecting the side bars of the sections, a support for swinging mounting of the upper section, guide means for the lower section to effect hinging of said hinge means when the lower section is raised in said guide means, means for raising the lower section in the guide means, and means attached to the upper section and cooperating with the raising means to anchor the sections in adjusted position.
20. 8. An awning including, upper and lower sections having side bars provided with a series of groove-like recesses, louvers having ends disposed in the recesses of said side bars, tie rods between selected louvers to retain said louvers in said recesses, and means hinging the sections together with the hinging axis coaxial with the plane of a lowermost louver in the upper section.
25. 9. An awning including, an upper section having side bars, louvers connecting the side bars, a lower section having similar side bars, louvers connecting the side bars of the lower section, tongues on the abutting ends of the side bars and hinge pins extending through said tongues, a frame, pins projecting from the side bars of the upper section and having pivotal mounting in sockets of the frame for swinging mounting of the upper section, and guide means in the frame for the lower section to effect hinging of said sections when the lower section is raised in the frame.
30. 10. An awning including, an upper section having side bars, louvers connecting the side bars, a lower section having similar side bars, louvers connecting the side bars of the lower section, tongues on the abutting ends of the side bars and hinge pins extending through said tongues, a frame, pins projecting from the side bars of the upper section and having pivotal mounting in sockets of the frame for swinging mounting of the upper section, guide grooves in the sides of the frame, and pins projecting from the lower section into the guide grooves.
35. 11. An awning including, an upper section having side bars, louvers connecting the side bars, a lower section having similar side bars, louvers connecting the side bars of the lower section, tongues on the abutting ends of the side bars and hinge pins extending through said tongues, a frame, pins projecting from the side bars of the upper section and having pivotal mounting in sockets of the frame for swinging mounting of the upper section, guide grooves in the sides of the frame, and pins projecting from the lower section into the guide grooves, said pins being of
40. 75.
45. 76.
50. 77.
55. 78.
60. 79.
65. 80.
70. 81.
75. 82.

a length to space the sections from the frame and the tongues from rubbing against each other.

12. An awning including, an upper louvered section and a lower louvered section, hinge means connecting said sections, a frame, means hinging the upper section in the frame at the top thereof, means for guiding the lower portion of the

lower section in the frame, means for raising the lower section in the guide means, and means attached to the upper section and cooperating with the raising means to anchor the sections in adjusted position.

TANDY BURR THURMAN.
